UNITED STATES PATENT OFFICE.

RICHARD H. STEVENS, OF PHILADELPHIA, PENNSYLVANIA.

GATE-OPERATING DEVICE FOR SHAFTS.

1,342,832.

Specification of Letters Patent.

Patented June 8, 1920.

Application filed November 7, 1918. Serial No. 261,516.

To all whom it may concern:

Be it known that I, RICHARD H. STEVENS, residing at Philadelphia, Philadelphia county, Pennsylvania, have invented a new and useful Improvement in Gate-Operating Devices for Shafts, of which the following is a full, clear, and exact description, reference being had to the accompanying drawings, forming part of this specification, in which—

Figure 1 is a partial side elevation partly broken away showing one form of my invention;

Fig. 2 is a partial view at right angles to Fig. 1, showing the cam guides on the cage and their relation to the clutch-operating mechanism;

Fig. 3 is a side elevation of the clutch-operating lever;

Fig. 4 is a side elevation partly broken away of the door-hoisting mechanism; and

Fig. 5 is a longitudinal section partly in elevation of the hoisting mechanism of Fig. 4.

My invention relates to apparatus for operating the gates or doors of shafts or elevators, and is designed to provide an improved system whereby the opening of the elevator door or gate is prevented, except when the cage is in proper position in front of the gate or door.

The main features of my invention lie in a gate-lifting mechanism having a clutch system which is automatically connected by the car when at the desired level, this mechanism also having a hand control to complete the chain of connections for lifting the gate or door.

The gate is closed by gravity, independently of the motor or power mechanism after the car leaves the landing. The power mechanism operates the gate only in opening, and the mechanism is simple and not liable to get out of order, there being no compressed fluid, such as air, used therein.

In the drawings, referring first to Figs. 1, 2, and 3, the shaft gate 2 moves vertically on side guides 3, 3. It is lifted by a cable 4, extending over pulleys 5 and 6, and thence down to the lifting mechanism hereinafter described. The cage, a portion of which is shown at 7, is provided with curved cam guides 8, 8, secured to its side, and preferably of the general form shown in Fig. 2. The flanges of these guides engage overhung roller 9, projecting inwardly from the lower

end of lever 10, projecting down from shaft 11 mounted in stationary bearing 12 at the side of the shaft. A spring-controlled rod 13 holds the roller 9 in proper position to enter the cage guides.

To the other end of shaft 11 is secured a sheave 14, which actuates wire rope 15, extending over rope sheave 16, secured to the shaft 17 of the door hoist.

The shaft 17 is rotatably mounted in a bearing on a housing 18, for a winding drum and its actuating mechanism. This actuating mechanism is clearly illustrated in Figs. 4 and 5, and comprises a hollow shaft 33, 70 mounted in bearing members 34 and 36, the bearing member 34 being formed integrally with the housing 18, while the bearing 36 is provided with a flange 37, seated in one end of the housing 18, to which it is secured. 75 This shaft 33 is held in position in the bearings by means of nuts 33^a threaded on the ends thereof. Rotatably mounted on the shaft 33 is a worm wheel 32, which meshes with a worm 39, secured to a driving motor 80 41 by means of a coupling 40, and is rotatably mounted in bearings 38 on the housing 18. This worm wheel 32 is held from endwise movement on the shaft 33 by means of a collar 35, shrunk on the shaft 33, or secured thereto in any desired manner. The worm wheel 32 is provided with a conical clutch member 31, which is arranged to be engaged by a similar clutch member 28, on a winding drum 27 for the cable 4. This winding drum 90 is rotatably mounted on the hollow shaft 33 along which it is adapted to move between frictional disks 30. These frictional disks 30 are connected to a clutch-actuating rod 26 by means of keys 29, which pass through 95 slots in the clutch rod 26, as well as slots in the shaft 33. Mounted on one end of this rod 26 is a crosshead 25, and interposed between said crosshead and the left-hand key, as viewed from Fig. 5, is a sleeve 45; and 100 42 is a spring interposed between the other side of said sleeve and nuts 44 on the end of the rod 26, for yieldingly holding the parts in the positions shown in Fig. 5. The other end of said rod is also provided with nuts 44^a, and interposed between said nuts and the right-hand key 29 is a sleeve 45^a. By adjusting either of the nuts 44 or 44^a, the tension of the spring 42 may be adjusted for varying the frictional contact between the 105 disks 30 and the hub of the drum 27. 21 is a bifurcated lever which is connected to the

crosshead 25, the one end of said lever being pivotally connected at 22 to one end of a link 23, which is, in turn, connected at 24 to the housing 18. The other end of this lever 21 5 is pivotally connected to a crank arm 19, on the shaft 17, by means of a link 20, the arrangement being such that when the shaft 17 is rocked clockwise, as viewed in Fig. 5, by the cable 15, the clutch member 28 will 10 be moved into engagement with a clutch member 31; and as soon as the electrical connections to the motor 41 are closed, as hereinafter described, the drum 27 will be rotated to wind up the cable 4 and thereby elevate the gate 2. The spring 42, through the medium of the disks 30, forms a brake for the drum 27 to prevent the spinning thereof when the gate is closed by gravity, and also provides a yielding connection between the 15 clutch members to permit one member to slip relative to the other, if the motor has not come to rest when the gate has been moved against its stop.

The electrical controlling device for the 20 motor 41 comprises a rod 46, movably mounted in guide 47. Extending outwardly from the gate 2 is a striker 48, which is adapted to engage a projection 49 on the rod 46, when the gate has been moved to a predetermined height in order to break the circuit to the motor 41. The motor 41 is connected by a wire 50 with one contact 51 of an electrical switch, the other contact 52 thereof being connected to a wire 53, leading from the source of current. The other wire 54 25 from the source of current leads directly to the motor 41. Pivotally connected at any suitable point on the framework at the proper height above the floor at which a car is to be stopped is a switch lever 55, having a finger 56, adapted to close the contacts 51 and 52. One arm of this lever 55 is arranged to be struck by a tappet 57 on the rod 46, when the gate has been moved to its proper 30 height to break the circuit to the motor 41.

In operation, as the cage nears the level of the floor, the guides 8 thereon actuate the particular roller 9 at that floor, and thus through a series of connections actuates the 35 clutch rod 26 and moves the clutch members 28 and 31 into engagement with each other. If the cage is stopped at this level, the operator then shifts the switch lever 55 from the full line position to the dotted line position, and closes the circuit to the motor 41. The rotation of the motor will rotate the worm 39 and the worm-wheel 32 and with it the drum 27 to wind up the cable 4 and lift the gate 2 from the full line position. 40 As the gate moves toward the dotted line position near the end of its movement, the tappet 48 thereon will engage the projection 49 on the rod 46 and lift said rod so that the 45 tappet 57 thereon will shift the switch lever

55, from the dotted line position to the full line position and break the circuit of the motor 41, and as the clutch members are in engagement with each other, the gate will be held in its elevated position. As soon as the 70 operator moves the cage from this floor level, the roller 9 will be actuated by the guides 8 to disconnect the clutch members 28 and 31, so that the gate 2 will move to its closed position by gravity. Any shock of the downward movement of the gate will be taken up by the spring or springs 43 surrounding the guides 3. The speed of the closing movement of the gate 2 is controlled by the frictional engagement of the disks 30 against the 75 hub of the drum 27, as before described.

It will be readily appreciated that the door can not be moved to its open position by its actuating mechanism, unless the cage is at that floor level to close the clutch. If the 80 electrical connections at that particular floor should be closed, when the cage passes said floor, the gate might be slightly raised by means of the motor, but as soon as the cage passed beyond the floor level, the clutch 85 would be disconnected so that the door will immediately close. It is therefore impossible to lift the door to a dangerous opening, unless the car is stopped in position opposite the landing, and the motor control switch is 90 closed by hand.

In the drawings, I have shown one form of electrical connections, although it will be understood that different forms of connections might be used for operating the motor. 100 It will also be understood that other types of motors, as well as actuating means for the motor, may be used than those disclosed in the drawings and described in the specification.

The advantages of my invention will be obvious to those skilled in the art, since a simple and effective mechanism is provided which effectually avoids a dangerous opening of the gate when the cage is not stopped 110 in landing position. The flexible connections controlled by the cage may lead in any desired direction so that the hoists may be placed in any desired location.

I claim:

1. In a door operating mechanism for shafts or elevators, a door arranged to normally move to its closed position, a drum, a flexible connection between the drum and the door, said drum being arranged to move 120 the door to its open position, an electric motor for actuating the drum, clutch connections between the drum and the motor, an automatic member in position for throwing the clutch into engagement, an actuating device on the cage or elevator for actuating the clutch connections to throw in the clutch when the cage is passing said member, an electric switch under the control of the operator for closing the circuit through 125 130

the motor, an automatic means arranged to be actuated by the door when it moves to its open position to open said switch to break the circuit to the motor, substantially as described.

5 2. In a door-operating mechanism for shafts or elevators, a door arranged to move to its closed position by means of gravity, a winding drum having a cable connected thereto and to the door for moving the door to its open position, an electric motor for actuating the drum, a clutch for connecting the motor to the drum, means actuated by the cage or elevator for throwing the clutch 10 members into engagement with each other, an electrical switch under the control of the operator for closing the circuit to the motor to rotate the drum and move the door to its open position, an automatic switch 15 arranged to be actuated by the door when it moves to its open position to break the circuit to the motor, and an automatic brake arranged to be set into operation when the cage is moved to release the clutch to prevent the drum from spinning; substantially as described.

20 3. In a door-operating mechanism for shafts or elevators, a door arranged to move to its closed position by means of gravity, a winding drum having a cable connected thereto and to the door for moving the door to its open position, an electric motor for actuating the drum, a clutch for connecting the motor to the drum, means actuated 25 by the cage or elevator for throwing the clutch members into engagement with each other, an electrical switch under the control of the operator for closing the circuit to the motor to rotate the drum and move the door 30 to its open position, an automatic switch arranged to be actuated by the door when it moves to its open position to break the cir-

cuit to the motor, and a spring brake arranged to be set into operation when the cage is moved to release the clutch to prevent the drum from spinning; substantially 45 as described.

4. In a door-operating mechanism for shafts or elevators, a motor having manual starting mechanism and connections actuated by the opening movement of the gate for cutting off the supply of actuating fluid to the motor, actuating connections between the motor and gate including a clutch, connections actuated by the movement of the cage arranged to open or close the clutch mechanism, the gate being arranged to close to normal position independently of the motor, and brake mechanism arranged to frictionally brake the closing of the gate or 50 door, substantially as described.

5. A door operating mechanism for elevator shafts, comprising a door adapted to normally move to closed position by gravity, means for opening said door, electrically 55 driven mechanism for said means, a normally inoperative clutch between said driving mechanism and said means, a clutch actuating member always arranged to be actuated by the elevator every time it reaches 60 a predetermined level to move said clutch into operative position and hold the same in such position as long as the elevator remains at said level, said clutch actuating member being arranged to be automatically 65 operated to move the clutch to its normally inoperative position when the elevator moves away from said predetermined level, and means for closing the circuit to said driving mechanism, substantially as described. 70 75 80

In testimony whereof, I have hereunto set my hand.

RICHARD H. STEVENS.
